UNITED STATES PATENT OFFICE.

PHILANDER R. GRAY, JR., OF ELIZABETH, NEW JERSEY.

FLUID-TRAP.

SPECIFICATION forming part of Letters Patent No. 417,171, dated December 10, 1889.

Application filed August 1, 1889. Serial No. 319,397. (No model.)

To all whom it may concern:

Be it known that I, PHILANDER R. GRAY, Jr., of Elizabeth, in the county of Union and State of New Jersey, have invented certain new and useful Improvements in Automatically-Acting Fluid-Traps, of which the following is a specification.

My invention relates to traps for use in steam-heating systems or refrigerative or other systems where the circulation or periodic discharge of a liquid is to be accomplished.

The invention consists in certain improved constructions and organizations, hereinafter described and claimed.

In the accompanying drawings, Figure 1 is a plan view of the interior mechanism, the casing being shown in horizontal section; Fig. 2, a vertical longitudinal section; Fig. 3, a transverse section on the line 3 3 of Fig. 2.

The shell or body A of the trap may be circular in cross-section and is formed at each end with flanges A', to which the heads or end pieces A² are bolted. On one side—that forming the bottom of the trap—the flanges A' are provided with feet a, which serve to lift the shell above the ground or floor.

B is the inlet-pipe, and C the outlet. The latter projects into the shell and is formed with or communicates with a flattened hollow chamber D, having a vertical screw-threaded hole through it, into which the screw-threaded valve-seat plug E screws. The valve-seat plug is formed with a central vertical passage-way e, in which the valve F is seated, as previously described, and with horizontal passages e', leading from the central passage into the chamber D. The bottom of the valve-seat plug is formed with an angular recess e², into which enters the correspondingly-shaped head

40 or end of a vertical screw-adjusting rod E', passing through the bottom of the shell. By means of this rod the valve-seat plug may be adjusted vertically in the chamber D. Within the shell, and preferably upon the outlet-pipe

45 C or chamber D, are two lugs or pivot-supports G H, on opposite sides of the valve F. In the latter a lever H' is pivoted, and the short end of this lever is pivotally connected with the valve F, while its longer end carries

50 a weight H². In the former a lever G' is pivoted, and the short end of this lever is pivotally connected with the valve F, while its

longer end is connected by a vertical link G² with the short end of a long horizontal lever I, arranged above the levers G' H' and pivoted in brackets I' I', mounted on the outlet end or head of the trap. The longer end of the lever I has swung from it an open bucket or a float K.

I is a fluid-gage of usual construction. 60

As will be perceived, this trap is operated by the difference in effective gravity between the weight H² and the bucket K, which in operating is filled by the liquid, the relative power of the two being varied by the fluid-level. The weight H² normally tends to open the valve F and permit the discharge of fluid from the trap, and this tendency is counteracted by the superior weight of the bucket K when the fluid-level is low; but as the level 70 of fluid rises, the effective weight of the bucket decreases and permits the valve F to open. By adjusting the valve-seat plug vertically, as before described, the elevation of the bucket, and consequently the level of the 75 fluid to be maintained, may be varied; or by this adjustment the relations of the weighted lever and bucket-levers may be so adjusted as to insure the operation of the trap.

I claim as my invention— 80

1. The combination, substantially as set forth, of the shell or casing having inlet and outlet pipes or passages, the outlet-valve, the weighted lever normally tending to open the valve, the float or bucket, and bucket-carrying 85 levers connected to the valve independently of the weighted levers.

2. The combination, substantially as set forth, of the shell or casing having inlet and outlet pipes or passages, the outlet-valve, the weighted lever normally tending to open the valve, and the float or bucket connected to the valve for closing it in the manner substantially as set forth. 90

3. The combination, substantially as set forth, of the shell, the removable head or end piece, the outlet-valve, the weighted lever for opening the valve, the float-levers connecting the float to the valve, and brackets secured to the end piece to which the float-levers are 100 pivoted.

4. The combination, substantially as set forth, of the outlet-chamber, as D, having the screw-threaded valve-seat opening therein,

the screw-threaded valve-seat working in said opening, and the valve-seat-adjusting rod removably connected therewith.

5. The combination, substantially as set forth, of the shell, the outlet-chamber supported therein, the vertically-adjustable valve-seat in said chamber, its adjusting-rod extending through the shell, the valve, the

weighted lever, the float or bucket, and its levers.

In testimony whereof I have hereunto subscribed my name.

PHILANDER R. GRAY, JR.
